UNITED STATES PATENT OFFICE.

GEORGE E. BATES, OF SYRACUSE, NEW YORK.

KEYHOLE-ILLUMINATING DEVICE.

1,349,360.

Specification of Letters Patent. Patented Aug. 10, 1920.

Application filed January 24, 1917. Serial No. 144,288.

To all whom it may concern:

Be it known that I, GEORGE E. BATES, a citizen of the United States, and a resident of Syracuse, in the county of Onondaga and State of New York, have invented a certain new and useful Keyhole-Illuminating Device, of which the following is a specification.

This invention has for its object the production of a door knob having an electric illuminating device associated therewith, and especially a particularly simple and efficient means by which the battery or cell is readily inserted and removed and the connections electrically broken and made both when the battery is being changed and when the light is being turned off and on. The invention consists in the novel features and in the combinations and constructions hereinafter set forth and claimed.

In describing this invention, reference is had to the accompanying drawings in which like characters designate corresponding parts in all the views.

Figure 1 is a front elevation of a door knob, and an escutcheon plate, the outer end wall of the knob being removed exposing the interior of the knob.

Fig. 2 is a side elevation of parts seen in Fig. 1, the door knob being shown in vertical section.

Fig. 3 is an end elevation of the battery or cell holder with a cell therein.

This invention comprises generally a hollow door knob provided with an incandescent electric lamp having a pair of terminals associated therewith and exposed on the interior of the knob, a battery or cell located in the door knob and having a pair of terminals for electrical connection with the former terminals, and means for supporting the battery or cell having detachable mechanical engagement with the knob whereby the supporting means is easily insertible and removable to change the battery, and during such movements carries the battery terminals into and out of electrical connection with the terminals associated with, or connected to, the lamp, one terminal of one pair being movable relatively to one of the terminals of the other pair for making and

breaking the circuit through the lamp. By lamp terminals is meant any terminals associated with the lamp. Although in this form of my invention the lamp terminals are what are technically known as lamp terminals.

1 designates the hollow door knob having a hub 2 mounted on the shank 3 carried by the usual escutcheon plate 4, the knob in this embodiment of my invention being shown as having its outer end wall 5 removable, and connected to the body of the door knob by a screw thread.

6 and 7 designate respectively the outer and central terminals associated with the lamp 8 and exposed on the interior of the door knob 1, these terminals being here shown as the lamp terminals themselves although they may be terminals of the lamp socket 9 or other terminals. The socket 9 is here shown as cut away to expose the lamp terminals.

10 is a holder for the battery or cell 11, the holder being arranged so that the battery or cell is arranged with its lengthwise axis crosswise of the axis of the door knob, said holder having detachable mechanical engagement with the door knob whereby it can be readily inserted and removed when the wall 5 of the knob is removed, so that the terminals 13 and 14 of the battery or cell will be moved by such movement of the battery holder into and out of position to make contact with the lamp terminals.

In this embodiment of my invention, the battery also has an additional movement to carry the battery terminals 13, 14 into and out of position to make and break the electrical connection between the battery and the lamp 8.

As here shown, the battery holder is a sheet metal shell having a stud 15 arranged in a suitable socket 16 in the knob, this socket being usually arranged coaxially with the axis of the knob. Said shell is also provided with a handle or finger piece 17 eccentric to the stud which handle extends through a slot 18 in the rear side of the door knob where it can be engaged in order to rock the battery holder 10 and the battery 11 to close the circuit between the battery

and the lamp 8. The movement of the holder by the handle 17 is against the action of a suitable returning spring 19 here shown as a tongue struck from the body of the sheet metal holder 10 and bent outwardly into position to engage the inner circumferential wall of the knob as shown in Fig. 1. This shell is also provided with lugs 20 at its lower end for limiting the movement of the battery into the holder, and is open at its upper end to permit the insertion and removal of the battery.

The shell is also provided with means as a spring tongue 21 struck therefrom for holding the battery therein, and also with an additional means as a spring tongue 22 bent to engage the end wall 5 and thus hold the shell with its stud 15 in the socket of the knob. The shell is preferably shaped to hold ordinary commercial batteries or cells now used in various forms of flash lights. Preferably, the holder is arranged to be moved to close the circuit in a direction opposite to that in which the knob is turned to unlatch the door.

In operation, when the knob is grasped by the hand, one finger thereof can be pressed against the handle 17 to rock the holder 10 and battery 11 to carry the terminal 13 into engagement with the outer terminal 6 of the lamp.

The battery terminal 14 is long enough to engage the central terminal of the lamp at all times so that during the rocking movement of the battery, this terminal 14 simply has a sliding contact with the central terminal of the lamp. When the terminal 13 makes contact with the lamp terminal, the lamp 8 is illuminated and lights the key hole 23 or other place to be illuminated.

When it is necessary to remove the battery the wall 5 of the knob is removed, the battery holder simply taken hold of and pulled outwardly, this movement disengaging the battery terminal 14 from the central lamp terminal and also moving the stud 15 out of the socket of the door knob. The battery is then removed by applying pressure to the lower end thereof, and the new battery inserted and the shell replaced, the replacing movement bringing the terminals 13 and 14 into operative relation to the lamp terminals, so that no wiring is necessary.

What I claim is:

1. The combination of a hollow door knob having a pair of electrical contact terminals located near each other and at one side of the shank of the knob, said terminals being exposed on the interior of the knob, a battery having terminals at one end, and means on the interior of the knob for holding the battery crosswise of the axis of the knob with the terminals at one end thereof in position to coat with the terminals of the knob, the battery being removable and

replaceable through the open front side of the door knob when the front wall is removed, substantially as and for the purpose described.

2. The combination of a door knob provided with a lamp arranged eccentric to the axis of the door knob, a battery mounted on the interior of the knob, and movable about an axis to make and break the connection between it and the lamp, and means exposed on the outside of the door knob for rocking the battery, substantially as and for the purpose described.

3. The combination of a hollow door knob provided with a lamp having terminals associated therewith and exposed on the interior of the knob, a battery in the door knob and being movable about the axis of the knob to carry its terminals into and out of operative contact with the former terminals, and means on the outside of the knob for rocking the battery, substantially as and for the purpose set forth.

4. The combination of a hollow door knob provided with a lamp having terminals associated therewith and exposed within the knob, a battery holder mounted within the door knob, and having means for detachable engagement therewith whereby the holder is supported by the knob, a battery carried by the holder and having terminals movable into and out of electrical contact with the former terminals during the insertion and removal of the battery holder, and means for effecting a relative movement of the battery holder, and the terminals associated with the lamp for making and breaking the circuit through the battery and lamp, said means being exposed on the outside of the door knob, substantially as and for the purpose set forth.

5. The combination of a hollow door knob provided with a lamp having terminals exposed within the knob, a battery holder mounted within the door knob, and having means for detachable mechanical engagement therewith whereby the holder is supported by the knob, and a battery carried by the holder and having terminals movable into and out of contact with the former terminals during the insertion and removal of the battery holder, the holder also having an additional movement for making and breaking the circuit between the battery and the lamp terminals, substantially as and for the purpose described.

6. The combination of a hollow door knob provided with a lamp having terminals exposed on the interior of the knob, a battery holder mounted in a door knob, a battery carried by the holder, the holder having means for detachable mechanical connection with the door knob whereby the holder is supported, the terminals of the battery being so arranged that they move into and out

of operative relation to the lamp terminals during the insertion and removal of the holder, the holder being also movable about an axis for carrying the terminals of the 5 battery into and out of operative contact with the lamp terminals, and means mounted on the outside of the knob for rocking the

holder, substantially as and for the purpose specified.

In testimony whereof I have hereunto 10 signed my name at Syracuse, in the county of Onondaga and State of New York, this 19th day of January, 1917.

GEORGE E. BATES.
